UNITED STATES PATENT OFFICE.

JOSEPH SCHIFFHAUER, OF CHICAGO, ILLINOIS.

SECTIONAL MOLD.

1,426,512.

Specification of Letters Patent. Patented Aug. 22, 1922.

Application filed September 21, 1921. Serial No. 502,093.

To all whom it may concern:

Be it known that JOSEPH SCHIFFHAUER, a citizen of the United States, residing at Chicago, in the county of Cook and State of Illinois, has invented certain new and useful Improvements in Sectional Molds; and he does hereby declare the following to be a full, clear, and exact description of the invention, such as will enable others skilled in the art to which it appertains to make and use the same.

The present invention relates to shaping devices and has to do particularly with molds for plastic materials and those which congeal on standing.

It is, primarily, my object to provide a mold comprising parts which may be quickly assembled, and, when assembled, form a rigid and substantially leak-proof vessel, the manner of assembling and securing together of the several parts producing complete co-operation therebetween.

Secondarily, it is my object to provide, in a sectional mold, a stand or support engaging the several sections one to another to seal the crevices therebetween, the stand itself adding to the stability and rigidity of the mold and rendering it liquid tight.

These and such other objects as may hereinafter appear are attained by the novel construction, arrangement and form of the several parts of the device to be described and claimed in the specification which follows. Reference will not be had to the drawing forming a part of this specification and in which:

Figure 1 is a side elevation of a complete device, one end being partly broken away to show how I secure correct registration of the mold sections;

Figure 2 is a bottom view;

Figure 3 is a vertical transverse section;

Figure 4 is a detail of one extremity of the stand for my device; and

Figure 5 is a transverse vertical section of a slightly modified form of stand.

Similar parts are referred to in the specification which follows and in the several figures of the drawing by like reference characters.

In the embodiment of my invention herein disclosed, the device comprises two mold sections 6^a and 6^b a stand 7, and a cover member 8.

Any desired figure may be depicted by the mold sections 6^a and 6^b, as, for example, the

pig shown in Figures 1 and 2. Said sections are conveniently stamped out of thin material but may be shaped in any other preferred manner. Along the bottom and ends of sections 6^a and 6^b are unbroken marginal flanges, designated by the ordinal 9. When the sections 6^a and 6^b are correctly registered one with another, these flanges 9 abut for their entire length and width.

To insure such registration, one section, say 6^a, has a seat shaped similarly to a ball seat and the other section, 6^b, is provided with a complementary projection, the registering means being designated 10 in the drawing. These means 10 are positioned close to the extremities of the flanges 9 for reasons later to be apparent, and, may be accurately and economically made by holding the mold sections 6^a and 6^b in proper alignment while allowing a round headed tool of small diameter to descend sharply upon flanges 9.

Along the upper edge of each section, 6^a and 6^b, flanges 11 are formed. These flanges follow the shape of the mold, generally, but have more regularity in their contour. If preferred, the edge of the material may be bent outwardly and back upon itself to provide a dull top edge for the sections 6^a and 6^b and, at the same time, to assist in preventing the accidental displacement of cover 8 therefrom.

Said cover 8 comprises a flat portion entirely covering the mold and is provided with a depending rim 12 sliding over and gripping the flanges 11 which it completely surrounds.

The body of the stand or support 7 is, substantially, of U shape in cross section, and may be cast, stamped or formed by any other available means. The longitudinal contour of the stand corresponds with that of the flanges on the mold sections 6^a and 6^b. The latter are adapted to be inserted into a trough or groove 13 extending at a uniform depth throughout the length of the stand 7.

A number of winged screws, 14, are arranged at intervals to penetrate one side of the body of stand 7, so that when sections 6^a and 6^b, properly registering one with another, are inserted into the trough or groove 13, the screws 14 on the one side of trough or groove 13, will bear against flange 9 of one section of the mold to force the flange 9 of the other section against the opposite wall of trough or groove 13 whereby to seal the

crevice between said flanges. Tightening of the screws 14, of course, increases the closeness of the contact between the flanges 9.

Bosses 15, as shown, are arranged upon stand 7 to allow a greater length of threads for each screw 14, reducing strain and increasing wear. At spaced points, laterally projecting legs 16, are provided for stand 7, said legs reinforcing the sides of the stand 10 7 as well as holding the device upright.

At each end of stand 7, one wall of the trough or groove 13 has a downwardly extending vertical groove 17 of sufficient diameter and extent to admit the registering means 10 (see Figure 4). Grooves 17 are provided to prevent the possibility of distortion of the sections 6^a and 6^b when in forced contact as well as to insure a proper seating of sections 6^a and 6^b in stand 7. 15 It will be noted that two of screws 14 are so positioned that when inwardly rotated they seat themselves squarely within the center of the depressed side of registration means 10, securing the mold sections 6^a and 6^b against 20 accidental displacement from the stand 7, no matter in what position said stand is held.

When the mold is wanted for use, the interiors of sections 6^a and 6^b are cleansed, 30 and, if necessary, coated or dusted. They are then placed together, correct relation being assured by registering means 10, after which the flanges 9 are inserted into trough 13 so that the oppositely disposed registering means 10 slide downwardly into grooves 17. Screws 14 are rotated until their further inward progress is prevented. The device is now ready to receive the material 35 for molding.

40 This is poured or pressed in and, if necessary, the mold is put aside for the material to congeal or become set, the cover 8 being slipped on to prevent bulging of sections 6^a and 6^b as well as to protect the contents of the mold.

45 To remove the molded material, the device may be disassembled in an order directly reversed to that of assembly with or without inversion of the mold, or the cover 8 may be made to serve as a receptacle for the molded material, in which event the mold is first inverted, cover on, and the stand 7 then removed, which removal will release sections 6^a and 6^b.

50 A modification of the stand member is shown in Figure 5. In the modification, the stand 7^a comprises a flat narrow sheet of material first folded to form an equal sided narrow V and then bent longitudinally to the proper shape to receive the flanges of the mold sections. The material of 7^a is flexible and is reinforced by the use of flexible feet 16', which resist the spreading of the V like body of the stand 7^a.

55 In either construction of the stand, the

sections of the mold are held together so tightly that material can not pass therebetween, but even if it should, the quantity would be so slight and so well intercepted in the trough of the stand (the bottom of 70 which abuts the flanges of the mold sections) that solidification would immediately ensue to seal the crevices against further leakage.

While I have made a complete disclosure 75 of my invention, I have not described each and every possible embodiment thereof, nor have I shown the changes, modifications, and alterations which the parts may undergo without departing from the spirit of 80 the invention. I do not, therefore, desire to be understood to limit myself to the specific embodiment of my invention here shown but, on the contrary, wish to include all forms of the invention falling within 85 the scope of the claims appended.

What I claim as new and desire to procure by Letters Patent of the United States, is:

1. A mold comprising sections, a stand 90 arranged to clamp said sections together, and means for aligning said sections, said aligning means cooperating with the stand to prevent displacement of the sections therefrom.

2. In combination, a mold comprising 95 sections having depending abutting flanges, and a stand adapted to close upon said flanges to seal the crevice therebetween, one of the sections having a pocket in its flange, the other of said sections having in its 100 flange a projection adapted to be inserted into said pocket when said sections are aligned, the stand having a groove adapted to admit said pocket.

3. In a mold comprising sections having 105 abutting flanges, a clamping member engaging said flanges, said clamping member comprising a grooved body having screws passing through one side thereof to engage the said flanges.

4. In combination, a mold comprising a 110 number of sections, having depending end and bottom flanges, the flange of one section being provided with pockets, the flange of the abutting section having projections 115 engaging in said pockets to register one section with the other, a flexible clamping member arranged to receive said flanges whereby to produce close contact therebetween, and a cover member for maintaining 120 the sections against bulging.

5. A mold comprising sectional mold members, said member being stamped from sheet material and having end, top and bottom flanges, the bottom and end flanges of 125 each section being continuous and abutting, a clamping member having a body longitudinally grooved to admit the end and bottom flanges, screw members penetrating one side of said body to force said end and bottom 130

flanges into close contact, the end flanges having at their upper extremities interfitting stamped depressions to hold the sections in alignment, the clamping member 5 having short vertical grooves within its longitudinal groove to admit the depressions in said flanges, additional screw members in said clamping member insertable into

said depressions to prevent displacement of the mold sections from the clamping member, and a cover member surrounding and engaging the top flanges of said sections to prevent distortion of said sections. 10

In testimony whereof I affix my signature.

JOSEPH SCHIFFHAUER.
